CLAIM

The ornamental design for a shower controller as shown and described.

DESCRIPTION

FIG. 1 is a front, bottom, left side perspective view of a shower controller showing our new design;

FIG. 2 is a left side view thereof;

FIG. 3 is a right side view thereof;

FIG. 4 is a top view thereof;

FIG. 5 is a bottom view thereof;

FIG. 6 is a front view thereof; and,

FIG. 7 is a rear view thereof.

The broken lines depict portions of the shower controller that form no part of the claimed design.
